I-BEAM CATHODE

Paul Haas, New Hyde Park, N. Y., and Albert L. Wilson, East Orange, N. J., assignors to Sylvania Electric Products Inc., a corporation of Massachusetts

Application February 19, 1948, Serial No. 9,456

14 Claims. (Cl. 250—27.5)

1

The present invention relates to electron discharge devices and more particularly to improved forms of cathode construction of such devices.

An object of the present invention is to increase the rigidity of internal construction of electron discharge tubes having relatively long flat cathodes.

Another object of the present invention is to increase the resistance to bowing of an elongated cathode of an electron discharge device.

Still another object of the present invention is the attainment of increased cathode efficiency in an electron discharge device over that heretofore obtainable.

In certain types of tubes, electrical requirements necessitate the use of relatively long elements, while at the same time, dimensional requirements necessitate the use of comparatively small diameter elements, closely spaced one from the other. Using cathode structures as known in the prior art, it was found that while the tubes resisted shocks in the direction of their length very well, the cathode, particularly, was liable to distortion as a result of acceleration in directions transverse to the length of the tube. When the cathode was elliptical, or of elongated rectangular form in transverse cross section, the cathode was particularly vulnerable to shock or acceleration in a direction normal to the major transverse dimension of the cathode.

In accordance with an aspect of the present invention, we provide a cathode, for use in such tubes, which is in cross section in the form of a hollow I. The cathode may thus be said to be an I-beam cathode.

Such a cathode may be constituted by attaching to the short transverse dimension of a hollow rectangular tube, metallic re-enforcing strips wider than the short dimension of the tube, and preferably of thicker material than the rectangular tube. These strips are welded or otherwise attached to the cathode tube so that their edges extend past the sides of the tube. In an end view the tube has the conformation of a hollow I. The electron emissive coating carried by cathode is preferably confined to the rectangular face of the cathode tube between the added metallic strips. Its thickness is equal to the distance the metallic strips extend past the sides of the tubing. The cathode as thus constituted is preferably heated by an insulated heater wire confined inside the hollow rectangular tubing. The cathode is surrounded by ancillary electrodes such as an anode and one or

2

more grid like electrodes and installed within an evacuated casing.

The present invention will be more fully understood by reference to the following detailed description which is accompanied by a drawing in which:

Fig. 1 illustrates, partially in section, an elevational view of an electron tube embodying the present invention, while

10 Fig. 2 is a transverse section of the tube shown in Fig. 1, taken along the lines 2—2 of Fig. 1, and Fig. 3 is a fragmentary elevation of a modification of the structure of Fig. 1.

In Fig. 1 there is shown an electron discharge 15 tube generally identified by reference character 10. The tube includes, within an evacuated casing 11, an indirectly heated cathode 12 surrounded by a number of ancillary electrodes such as a control grid 14 and a plate or anode 16. 20 If desired, additional grids may be provided between the control grid 14 and the anode 16. The cathode, control grid, and anode are maintained within the envelope 11 in their proper relative position by means of insulating spacers 18 and 19 through which pass support rods for the grid and plate, while cathode 12 itself extends through the insulating spacers 18 and 19. The cathode is heated by an insulated heater wire 22 within its hollow interior, and adapted 25 to be connected to a suitable source of electrical energy by leads 23 extending through the base of the tube envelope. Additional leads, such as leads 24, are provided for connection to the anode, cathode, and control grid.

30 The cathode 12 may be constructed of a length of thin-walled rectangular tubing 26 having secured to the short sides thereof metallic re-enforcing strips 30 and 31. Preferably metallic strips 30 and 31 are considerably thicker than 35 the thickness of the rectangular tubing 26 forming the body of the cathode and somewhat wider than the shorter transverse dimension of tubing 26. Thus, as shown more clearly in Fig. 2, the tubing 26 and metallic strips 30 and 31 form an 40 I-beam structure which has improved resistance to bowing along its length. The usual emitting coating carried by the tubular cathode is confined to the long faces of the rectangular tubing 26 between the metallic strips 30 and 31. Its 45 depth is preferably equal to the distance that the metallic strips extend past the sides of the tubing. Thus, the exterior of the completed cathode is substantially rectangular in configuration. If desired, in manufacturing the cathode, the thickness of the emitting coating may be

definitely determined by striking a straight edge along the edges of strips 30 and 31.

As indicated in Fig. 1, the strips 30 and 31 are preferably slightly shorter in length than the distance between spacers 18 and 19. Thus, short spaces, such as that indicated by reference numeral 33, are left at the top, and/or bottom, of strips 30 and 31. Some such spacing is desirable, as otherwise when the cathode is heated and expands longitudinally, the spacers 18 and 19 will either be forced further apart or the cathode may be placed under sufficient columnar stress to cause it to bow.

In the modification of the invention shown in Fig. 3, the same reference characters are applied to parts which correspond to those already described with reference to Fig. 1. Thus, it will not be necessary to again describe these parts in detail. However, in Fig. 3 the metallic strips 30 and 31 are extended through the cathode aperture in spacer 18 in the form of lugs 40 and 41 which may, if desired, be bent outwardly from the cathode sleeve 26 to a slight extent, to serve as a means for anchoring the cathode sleeve in position.

While we have shown and particularly described a number of embodiments of our invention, it is to be distinctly understood that our invention is not limited thereto, but that modifications within the scope of the invention may be made.

What we claim as our invention is:

1. An indirectly heated cathode including an elongated hollow rectangular metal tube, a strip of metal secured on each of a pair of opposing sides of said tube, said strips being wider than said sides.
2. An indirectly heated cathode including an elongated hollow rectangular metal tube, a strip of metal secured on each of a pair of opposing sides of said tube, said strips being of thicker material than said tube and wider than said sides.
3. An indirectly heated cathode including an elongated hollow rectangular conductive tube, a strip of metal secured on each of a pair of opposing sides of said tube, said strips being of thicker material than said tube and wider than said sides, and electron emissive material on the other sides of said tube.
4. An indirectly heated cathode including an elongated hollow rectangular tube, a strip of material secured on each of a pair of opposing sides of said tube, said strips being of thicker material than said tube and wider than said sides, and electron emissive material on the other sides of said tube, the surface of said material being flush with the edges of said strips.

5. An indirectly heated cathode including an elongated hollow rectangular metal tube, a strip of metal secured on each of a pair of opposing sides of said tube, said strips being of thicker material than said tube and wider than said sides, and electron emissive material on the other sides of said tube, the surface of said material being flush with the edges of said strips, said strips being shorter than the length of said tube.

6. An electron discharge device including an elongated cathode, an anode coaxially arranged about said cathode, said cathode being in the form of an elongated hollow rectangular metal tube, said cathode passing through insulating spacers at each end thereof, said cathode having a strip of metal secured on each of a pair of opposing sides of said tube, said strips being of thicker material than said tube and wider than said sides.

7. An electron discharge device including an elongated cathode, an anode coaxially arranged about said cathode, said cathode being in the form of an elongated hollow rectangular metal tube, said cathode passing through insulating spacers at each end, said cathode having a strip of metal secured on each of a pair of opposing sides of said tube, said strips being of thicker material than said tube and wider than said sides, and electron emissive material on the other sides of said tube.

8. An electron discharge device including an elongated cathode, an anode surrounding said cathode, said cathode being in the form of an elongated hollow rectangular metal tube, said cathode passing through insulating spacers at each end, said cathode having a strip of metal secured on each of a pair of opposing sides of said tube, said strips being wider than said sides, and electron emissive material on the remaining sides of said tube, the surface of said material being flush with the edges of said strips.

9. An electron discharge device including an elongated cathode, an anode surrounding said cathode, said cathode being in the form of an elongated hollow rectangular metal tube, said cathode passing through insulating spacers at each end, said cathode having a strip of metal secured on each of a pair of opposing sides of said tube, and electron emissive material on the remaining sides of said tube, the surface of said material being flush with the edges of said strips, said strips being slightly shorter than the distance between said insulating spacers.

10. An electron discharge device including an elongated cathode, an anode surrounding said cathode, said cathode being in the form of an elongated hollow rectangular metal tube, said cathode passing through insulating spacers at each end, said cathode having a strip of metal secured on each of a pair of opposing sides of said tube, said strips being wider than said sides, and electron emissive material on the remaining sides of said tube, said strips being bent away from said tube after passing through said spacers.

11. An electron discharge device including a cathode and a number of ancillary electrodes, said cathode being in the form of an elongated hollow tube having an I cross section, there being electron emissive material along the side portions of the I, the surface of said material being flush with the edges of the tube.

12. An electron discharge device including a cathode and a number of ancillary electrodes surrounding said cathode, said cathode being in the form of an elongated hollow metal tube having a cross section in the form of a hollow elongated rectangle, and a metal strip along each of a pair of opposite sides of the tube, said strips being of thicker material than the material of said tube and wider than said sides.

13. An electron discharge device including a cathode and a number of ancillary electrodes surrounding said cathode, said cathode being in the form of an elongated hollow metal tube having a cross section in the form of a hollow elongated rectangle, and a conductive strip along at least one of the narrow sides of the tube, said strip being of thicker material than the material of said tube and wider than the narrow sides, electron emissive material on the wide sides of said tube, and means within said tube for heating said cathode.

14. An electron discharge device including a cathode and a number of ancillary electrode sur-

rounding said cathode, said cathode being in the form of an elongated hollow tube having a cross section in the form of a hollow elongated rectangle, and metal strips along each of the narrow sides of the tube, said strips being of thicker material than the material of said tube and wider than the narrow edges, and electron emissive material on the wide edges of said tube between said strips, the surface of said electron emissive material being flush with the edges of said strips. 10
